UNITED STATES PATENT OFFICE.

HERMAN J. SCHOEN, OF BROOKLYN, NEW YORK.

SAFETY ATTACHMENT FOR GAS-BURNERS.

No. 902,917.

Specification of Letters Patent.

Patented Nov. 3, 1908.

Application filed March 4, 1908. Serial No. 419,074.

To all whom it may concern:

Be it known that I, HERMAN J. SCHOEN, a citizen of the United States, and a resident of Brooklyn, in the county of Kings and 5 State of New York, have invented certain new and useful Improvements in Safety Attachments for Gas-Burners, of which the following is a specification.

My invention relates to improvements in 10 safety attachments for gas burners.

Gas cocks of burners are sometimes turned to open position through accident or ignorance, allowing gas to escape into rooms and cause the death or sickness of the occupants, 15 an explosion or if nothing worse, a waste of gas.

My invention therefore has for its object 20 the provision of a simple, effective, durable and inexpensive attachment for gas burners, adapted to be attached or removed from gas burners with great facility and to prevent gas cocks from being turned to open position through accident or ignorance, thereby eliminating, to a great degree, the chances of 25 occurrences of the nature above mentioned.

In the drawings:—Figure 1 is a side view 30 of a gas burner having my safety attachment applied thereon. Fig. 2 a vertical sectional view taken on the line 2—2 of Fig. 1. Fig. 3 a horizontal sectional view taken on the line 3—3 of Fig. 1 showing the position 35 the arm of my safety attachment occupies when locking the burner cock or preventing it from being turned to open position. Fig. 4 a horizontal sectional view taken on the same line as Fig. 3 and showing, in full lines, 40 the position the arm of my safety attachment occupies after the burner cock has been turned to full open position and in dotted lines the position said arm occupies when 45 the burner cock is turned to partially open position, and Fig. 5 a fragmentary detail view, on an enlarged scale, showing the screw for locking the arm which locks the gas cock, 50 said screw being shown in full lines, in the position it occupies when locking said arm and in dotted lines in the position it occupies when withdrawn to allow said arm to be moved to unlock the gas cock.

Like reference characters designate 55 corresponding parts in the figures of the drawings illustrating my invention.

Referring to the drawings, 1 designates the body of a gasburner which is secured to a serv- 55 ice pipe and has a stop flange 2, 3 the burner cock thereof having a thumb and finger hold 4

affording means for turning it and a stop pin 5 adapted to contact with the stop flange, on one side of the body, when the burner cock is turned to or is in closed position. All of 60 these parts and their operation being well known the above reference is thought sufficient and I will now describe the construction of my safety attachment and its operation in connection with a gas burner to produce the desired results above referred to. 65

My safety attachment embodies a support having a bottom 6 provided with a stop lug or abutment 7 extending upwardly from its forward end in the line of movement of the 70 stop pin and adapted to be engaged thereby when the burner cock is turned to or is in open position, a long side 8 and a short side 9 integrally formed with said bottom at its rear end and a portion 10 hinged at 11 to 75 the top of the short side and forming therewith a side of equal length to the long side, the portion 10 and that portion of the long side opposite thereto being curved so as to closely embrace the body 1 of gas burner 80 and their upper ends abutting and being provided with threaded holes which receive the shank of a screw 12 and afford means for clamping the sides together and securing the support on the gas burner or for 85 allowing it to be removed therefrom.

An arm 13 is fulcrumed on a pin 14 projecting upwardly from the rear end of the bottom 6 of the support, the forward end of said arm curving around one side of the 90 burner cock 3 and the stop flange 2 in a horizontal plane and then depending downwardly in front of the thumb and finger hold 4 of the burner cock and having an enlargement 15 affording means for the engagement of the thumb to move the arm laterally and the horizontal portion of the arm having a shoulder or abutment 16 normally located in the path of movement of the stop pin 5 95 and bearing against one side thereof when the burner cock is in closed position and preventing it from being turned to open position. 100

A screw 17 is inserted through a threaded hole in the side 9 in the same plane with the arm 13 and its end normally located far enough therefrom to allow said arm to be forced laterally to disengage its shoulder or abutment 16 from the stop pin 5 and permit the burner cock to be turned to open position 105 and a spiral spring 18 is supported on said screw, one end bearing against the side 9 110

and the other end against the arm 13, and serves to normally yieldably hold said arm in its normal inward position with its shoulder or abutment in engagement with the stop pin 5 and prevent the burner cock 3 from being turned to open position and yet allow the arm to be forced outwardly by the lateral pressure of the thumb against its enlargement 15 to disengage its shoulder or 5 abutment 16 from the stop pin 5 and allow the burner cock 3 to be turned to full open position, bringing its stop pin 5 into engagement with the stop lug or abutment 7 on the support. When it is desired to lock the arm 10 13 so as to hold the burner in closed position, the screw 17 is turned until its end comes into contact with said arm.

From the foregoing description considered in connection with the accompanying drawings it will be readily understood, assuming the parts of my attachment to be in the position shown by full lines in Figs. 1 to 4 inclusive, that the burner cock is locked in closed position and that it can be unlocked 20 and turned to open position by forcing the arm laterally and returned to closed position and locked by turning it in the reverse direction, which will cause its pin 5 to ride against the arm 13 forcing it outwardly 25 against the action of the spring 18 and then allowing said arm to be forced inwardly again by the spring 18 when the pin 5 engages the shoulder or abutment 16 and it will also be understood from said figures of 30 the drawings and Fig. 5 thereof that when the screw 17 is turned inwardly bringing its end against the arm that said arm will be locked.

What I claim is:—

40 1. A safety attachment for gas burners embodying a support adapted to be secured thereon and an arm fulcrumed on said support and having an abutment normally located in the path of movement of the stop pin of the burner cock and preventing said burner cock from being turned to open position and a depending portion located adjacent said burner cock and affording means for forcing said arm laterally to withdraw 45 its abutment from the path of movement of the stop pin of the burner cock and allow said burner cock to be turned to open position, substantially as described.

50 2. A safety attachment for gas burners, embodying a support adapted to be secured thereon, an arm fulcrumed on said support and having an abutment normally located in the path of movement of the stop pin of the burner cock and preventing said burner cock from being turned to open position and a depending portion located adjacent said burner cock and affording means for forcing said arm laterally to withdraw its abutment from the path of movement of the stop pin 55 of the burner cock and allow said burner

cock to be turned to open position and means yieldably holding said arm with its abutment in the path of movement of the stop pin of the burner cock, substantially as described. 70

3. A safety attachment for gas burners, embodying a support adapted to be secured thereon, an arm fulcrumed on said support and having an abutment normally located in the path of movement of the stop pin of the burner cock and preventing said burner cock from being turned to open position and a portion located adjacent said burner cock and affording means for forcing said arm laterally to withdraw its abutment from the path of movement of the stop pin of the burner cock and allow said burner cock to be turned to open position means yieldably holding said arm with its abutment in path of movement of the stop pin of the burner 75 cock, and means for locking said arm, substantially as described. 80 85

4. A safety attachment for gas burners, embodying a support adapted to be secured thereon and having an abutment adapted to be engaged by the stop pin of the burner cock when said burner cock is turned to open position and an arm having an abutment normally located in the path of movement of the stop pin of the burner cock and preventing said burner cock from being turned to open position and a depending portion located adjacent said burner cock and affording means for forcing said arm laterally to withdraw its abutment from the path of movement of the stop pin of the burner cock and allow said burner cock to be turned to open position, substantially as described. 90 95 100

5. A safety attachment for gas burners, embodying a support adapted to be secured thereon and having an abutment adapted to be engaged by the stop pin of the burner cock when said burner cock is turned to open position an arm having an abutment normally located in the path of movement of the stop pin of the burner cock and preventing said burner cock from being turned to open position and a portion located adjacent said burner cock and affording means for 105 110 115 forcing said arm laterally to withdraw its abutment from the path of movement of the stop pin of the burner cock and allow said burner cock to be turned to open position and means for locking said arm, substantially as described. 120

6. A safety attachment for gas burners, embodying a support adapted to be secured thereon and having an abutment adapted to be engaged by the stop pin of the burner cock when said burner cock is turned to open position, an arm having an abutment normally located in the path of movement of the stop pin of the burner cock and preventing said burner cock from being turned to 12 125 130

open position and a depending portion located adjacent said burner cock and affording means for forcing said arm laterally to withdraw its abutment from the path of movement of the stop pin of the burner cock and allow said burner cock to be turned to open position and means yieldably holding said arm with its abutment in the path of movement of the stop pin of the burner cock, substantially as described.

7. A safety attachment for gas burners, embodying a support adapted to be secured thereon and having an abutment adapted to be engaged by the stop pin of the burner cock when said burner cock is turned to open position, an arm having an abutment normally located in the path of movement of the stop pin of the burner cock and prevent-

ing said burner cock from being turned to open position and a portion located adjacent 20 said burner cock and affording means for forcing said arm laterally to withdraw its abutment from the path of movement of the stop pin of the burner cock and allow said burner cock to be turned to open position 25 means yieldably holding said arm with its abutment in the path of movement of the stop pin of the burner cock, and means for locking said arm, substantially as described.

Signed at New York city in the county of 30 New York and State of New York this 20th day of February A. D. 1908.
